UNITED STATES PATENT OFFICE.

JAMES NIGHTINGALE, JR., OF NEW YORK, N. Y.

TAKE-UP AND LET-OFF MECHANISM FOR LOOMS FOR WEAVING BROAD SILK,

SPECIFICATION forming part of Letters Patent No. 351,934, dated November 2, 1886.

Application filed March 6, 1886. Serial No. 194,251. (No model.)

To all whom it may concern:

Be it known that I, JAMES NIGHTINGALE, Jr., of the city, county, and State of New York, have invented a new and Improved Take-Up and Let-Off Mechanism for Looms for Weaving Broad Silk, of which the following is a full, clear, and exact description.

The invention consists in the construction, arrangement, and combination of parts and details, as will be fully described and set forth hereinafter, and claimed.

Reference is to be had to the accompanying drawings, forming a part of this specification, in which similar letters of reference indicate corresponding parts in all the figures.

Figure 1 is a side view of a loom provided with my improvements, parts being broken out and others in section. Fig. 2 is a front view of the same. Fig. 3 is a rear view of the same. Fig. 4 is an enlarged detail sectional view showing the cloth-beam, the lay, and the mechanism for revolving the cloth-beam.

A is the frame; B, the heddles, which are worked in the usual manner, and C is the lay, on the top of which is held the shuttle-race C' and the reed C². The warps D are wound on the warp beam D', journaled in the frame A, and are passed from the said warp-beam downward and under a roller, E, pivoted in a frame, E', arranged to slide between the rear uprights, A', of the frame. From the said roller E' the warps pass upward and over the rollers F and F', on the top of the frame, then downward under the roller F', and through the reed C², and the finished fabric G passes over the breast-beam G', under the front bar, G², in the breast-beam G', over a stationary rod, G³, under a vertically-adjustable rod, G⁴, over the stationary rod G⁵, and then downward behind the cloth-beam H, under a roller, H', at the bottom of the frame, then up and around the cloth-beam. The rod G⁴ is adjusted by means of the screws G⁶, (see Fig. 6,) or in any suitable manner.

The frame E' has considerable weight, and, if desired, it may be weighted still more by a weight suspended from the same. The roller H' is journaled in the ends of arms I, pivoted to the sides of the frame in such a manner

that their free ends can swing vertically, and

on the said levers or arms I a box, I', is held, which serves to receive a weight; or the levers I can be weighted at or near their free ends in any other suitable manner. A lever, J, pivoted at its top to the side of the frame, has its lower end connected with the lay C, thus causing the said lever J to swing with the lay.

To the lever J a pawl, J', is pivoted, which is provided at its outer end with a dog, J², adapted to engage with the teeth of a gear or change-wheel, J³, mounted on the same shaft with a pinion, J⁴, which in turn engages with a cog-wheel, K, mounted on the same shaft with a pinion, K', engaging with a gear-wheel, K², mounted on the same shaft with the cloth-beam H, whereby the cloth-beam H is revolved by means of the said intermediate gearing from the lay C. A curved bar, L, secured to one of the levers I, projects upward, and its upper end is below the front end of the pawl J', so that when the levers I are raised the curved rod L will raise the pawl J' to such an extent that its dog J² can no longer engage with the teeth of the ratchet-wheel J³ and revolve the same, and consequently cannot revolve the cloth-beam.

Check-dogs or pawls L', resting on the edge of the wheels J³, are pivoted to an arm, L², projecting from the front of the loom. Two angle or elbow levers, M and M', are pivoted to the frame of the loom at the front and bottom in such a manner that their inner ends overlap and their outer upwardly-projecting ends, M², rest against the roller H', as shown in Fig. 2. By pressing down the inner end of the upper lever, M', the short arms M² of both the said levers M and M' are pressed upward, and the roller H' is thus raised.

The arrangement of the picker-staffs, the construction of the lay, shuttle-race, reed, heddles, &c., is the same as in other looms. The warp-beam D' is provided with the usual tension-rope, N, and weight N', for the purpose of holding the warps taut, the same as in other looms.

The operation is as follows: The fabric is produced in the same manner as in other looms, and is wound on the cloth-beam H, which is revolved in the manner set forth. When a certain quantity of the fabric has been

wound on the cloth-beam, the tension on the completed fabric passing over the roller H' and in the warps becomes greater, and is sufficient to raise the weighted levers I and the roller H' slightly. By this movement of the levers I the bar L is raised, and in turn raises the pawl J', carrying the dog J², so that the said dog cannot engage with the teeth of the ratchet-wheel J³, and the cloth-beam H is no longer revolved. The fabric formed is taken up by the action of the weighted levers I on the said fabric, as the roller H', journaled in the said weighted levers I, draws the fabric downward. The levers I descend sufficiently to permit the dog J² to drop on the toothed edge of the wheel J³ again, whereby the said wheel J³ is again revolved and the cloth wound on the cloth-beam. The tension on the fabric and warps is thus obtained from the weighted levers I and not directly from the cloth-beam, as in other looms. If at this time the operator wishes to let the fabric back to the reed, he presses down the levers M M', which raise the roller H' and permit the frame E', acting on the warps passed over the roller E, pivoted to the said frame, to pull the warps downward, whereby the fabric G is moved in the direction of the arrow a', Fig. 4. Should the filling break or run out while the loom is running, then there is no blank space formed in the fabric G, and as soon as the weaver discovers that the filling has broken or run out he moves the fabric in the direction of the arrow a', as above described, so as to bring the last west thread up to the reed C² on the lay and there remedies the running out or breaking of the filling in the usual manner. If the weaver has occasion to undo a few picks for any defect that might happen to the fabric in the breaking of a thread between the reed and the breast-beam, he moves the fabric in the direction before described toward the reed in the direction of the arrow a', and corrects this defect in the usual manner. In all cases this adjustment of the fabric to the reed is entirely independent of the cloth-beam, the only function of which is to carry the completed fabric, but not to give the same any tension. The cloth-beam is empty at the beginning of the weaving, and as the gear or change wheel J³ turns a little faster, according to the desired number of picks per inch of the fabric, there is a tendency to move the weighted lever I upward, and such raising will take place at quite long intervals at first, until the cloth-beam becomes

more and more filled with the fabric woven, so that the intervals between the raising and lowering of the weighted lever I become more frequent, according to the quantity of the fabric on the cloth-beam; but as the diameter of the winding-surface of the cloth-beam increases, and the quantity of the fabric wound on the cloth-beam for each revolution increases with it, it is evident that the weighted levers I will be raised much sooner than when there is a small quantity of fabric on the cloth-beam.

Having thus fully described my invention, I claim as new and desire to secure by Letters Patent—

1. The combination, with a loom-frame, the warp-beam, the heddles, and the lay, of the cloth-beam, mechanism for revolving the said cloth-beam from the lay, levers I, pivoted to the loom-frame, a roller, H', journaled in the ends of the levers I below the cloth-beam, and a lever, M', pivoted on the loom-frame and having one end, M², resting against the roller H', substantially as herein shown and described. 80
2. The combination, with a loom frame, the warp-beam, the heddles, and the lay, of the cloth-beam, mechanism for revolving the said cloth-beam from the lay, levers I, pivoted to the loom-frame, a roller, H', journaled in the ends of the levers I below the cloth-beam, and angle-levers M M', pivoted to the loom-frame, their outer angular ends, M², resting against the roller H' and their inner ends overlapping, substantially as herein shown and described. 90
3. The combination, with a loom-frame, heddles, a lay, a cloth-beam, and a warp-beam, of a vertically-sliding frame, a roller journaled in the same, over which roller the warps are passed, levers pivoted to the loom-frame, a roller journaled in the ends of said levers below the cloth-beam, a pawl operated from the lay, a ratchet-wheel operated from the said pawl, gearing for operating the cloth-beam from the ratchet-wheel, an arm projecting upward from one of the levers in which the roller below the cloth-beam is journaled, and levers for raising the levers in which the roller below the cloth-beam is journaled, substantially as herein shown and described. 100
